UNITED STATES PATENT OFFICE.

HORACE E. SMYTHE, OF PITTSBURGH, PENNSYLVANIA.

FURNACE.

Application filed February 28, 1921. Serial No. 448,684.

To all whom it may concern:

Be it known that I, HORACE E. SMYTHE, a citizen of the United States, residing at Pittsburgh, in the county of Allegheny and State of Pennsylvania, have invented new and useful Improvements in Furnaces, of which the following is a specification.

My invention relates to a combined furnace and air regenerating means, wherein the entrance of air to the regenerators is controlled by valves preferably of the poppet or mushroom type.

The object of the invention is to provide a gas-burning reversing furnace with air regenerators whereby the air supply for preliminary combustion and the air supply for complete combustion may be separately regulated, preferably by valves supplying air to the regenerators. Other objects appear hereinafter.

Referring to the accompanying drawings, Fig. 1 is a horizontal section of my invention taken on two planes, the section of the upper and lower portions being respectively taken on levels indicated by the lines I—I and I^a—I^a of Fig. 2; Fig. 2, a vertical longitudinal section on the line II—II of Fig. 1, the upper part following the line II^a—II^a of Fig. 3; Fig. 3, a central vertical longitudinal section of one end of the furnace, the section being along the line III—III of Fig. 4; Fig. 4, a horizontal section on the line IV—IV of Fig. 3; and Fig. 5, a vertical section on the line V—V of Fig. 1. Fig. 5 is also a section of the structure shown on the line V^a—V^a of Fig. 1, with the reference numerals 17 and 17' of Fig. 5 changed to 16 and 16'.

On the drawings, I have shown, except on Fig. 4, only one end of a reversing furnace, and only a single section in a single plane of each pair of regenerators, but it is to be understood that the omitted end of the furnace is constructed precisely like that shown, and that both pairs of regenerators are precisely alike. The parts of the two sets of regenerators have the same numerals except that those of one set have prime marks added.

1 designates the melting chamber having centrally beyond each end thereof the arched-over combustion chamber 2 opening outwardly toward the melting chamber and downwardly at its rear end into the air flue 3 leading downwards to the passage 4.

At each side of the arched chamber 2 is

a flue 5, opening into the furnace chamber 6 which opens into the chamber 1. The flues 5 lead below to the passage 7 parallel with, and at the side of, the passage 4. 60

Each pair of regenerators has its regenerator chambers 8 and 9, separated by the partition wall 10, which is an extension of the partition wall 11 separating the passages 4 and 7. Each regenerator 8 lies at 65 the side of a regenerator 9 and they are connected respectively at one end to the passages 7 and 4 by the passages 12 and 13, and at the other end to the separate valve chambers 14 and 15 by the separate passages 16 and 17 provided with the blast pipes 18. Each valve chamber has an inlet 19 closed by a mushroom or poppet valve 20 and an outlet 21 closed by a mushroom or poppet valve 22. The outlets of all the chambers 14 and 15 lead to the stack chamber 23 leading to the stack flue 24, having the damper 25.

Gas is fed into the sides of the preliminary combustion chamber 2 by the pipes 26" between the flue 3 and the chamber 1 and into the combustion chamber 2' by the pipes 26¹⁰ between the flues 3' and the chamber 1. 70

Assuming that the valves 20 and 22 for 85 the chambers 14 and 15 at the upper side of Fig. 1 are as shown on the left side of Fig. 3, and that the valves in the other chambers 14' and 15' are as shown on the right side of Fig. 5, fresh air enters the 90 open ports 19, whence it passes through the flues or passages 16 and 17 to the respective regenerators 8 and 9. From the regenerator 9 air goes through the passages 13 and 4 and the flue 3 to the combustion 95 chamber 2 to support the combustion of the gas issuing from the gas pipes 26, while air passes from the regenerator 8 through the passages 12 and 7 and the flues 5 to the chamber 6 and thence to the chamber 1 100 to complete the combustion of the gas. The burning gases pass through the chamber 1 and thence in a reverse direction through the other end of the furnace in a well known manner down the flues 3' and 5' to the regenerators 8' and 9' and thence through the flues 16' and 17' to the valve chambers 14' and 15' and thence down through the open ports 21' to the chamber 23 and stack flue 24. Blast may be applied to one or 105 both the pipes 18 as may be necessary or desired, or the valve 20 for one port 19

110

may be closed or one or both may be partly closed to introduce the required amount of air to the different flues 3 or 5 or both. To reverse the furnace, the gas is cut off from the gas pipes 26" and turned on to the pipes 26¹⁰. The position of the valves 20, 20', 22, and 22' are all reversed from the positions shown on Fig. 5. Air will then pass through the ports 19' and through the flues 16' and 17' to the regenerators 8' and 9' and thence in an obvious manner from the lower part of Fig. 1 to the flues 3' and 5' to the combustion chamber 2' and the chamber 1 and down the flues 3 and 5 and through the regenerators 8 and 9 and the flues 16 and 17 to the stack chamber 23 by way of the open ports 21.

The description just given requires natural draft for the air, but in case forced draft is used, the valves 20 will be closed for the regenerators taking in fresh air, which will be taken in through the blast pipes 18. Upon reversal of the furnace the valves 20' and 22' will be closed and the valves 20 closed and the valves 22 opened, fresh air being taken in through blast pipes (not shown) for the other regenerators. Natural draft may be used for one regenerator 8 or 8' and forced draft used for the other regenerator 9 or 9'.

At the rear end of the regenerators 8 and 9 are the arched passages 25 and 26 extending transversely of the passages 16 and 17 and communicating therewith. The passages 25 and 26 are unobstructed and provide a large amount of room for the air and gases passing between the regenerators and the passages 16 and 17. These passages 25 and 26 do away with a large amount of friction of the air and waste gases in the spaces usually occupied by checkerwork.

I claim:

1. A furnace structure having a melting chamber, a preliminary combustion chamber at each end thereof, and means supplying fuel gas to each combustion chamber, in combination with two pairs of air regenerators, means connecting one member of each pair to the respective combustion chambers, means connecting the other member of each pair to the respective ends of the furnace chamber to complete combustion and

protect the roof of the latter chamber, a stack flue, separate passages leading outwardly from each regenerator, a valve chamber, one for each passage, the chamber being outside the furnace structure, a poppet valve to admit fresh air to each chamber, and a poppet valve to admit waste gases from each chamber to the stack flue, whereby fresh air may be admitted in regulated quantities to each regenerator of either pair of regenerators while the stack flue may be connected to carry out waste gases from the remaining pair of regenerators.

2. A furnace having a melting chamber, a preliminary combustion chamber at each end thereof, and means supplying fuel gas to each combustion chamber, in combination with two pairs of air regenerators, means connecting one member of each pair to the respective combustion chambers, means connecting the other member of each pair to the respective ends of the furnace chamber to complete combustion and protect the roof of the latter chamber, a stack flue, separate passages leading outwardly from each regenerator, a valve chamber, one for each passage, the chamber being outside the furnace structure, a poppet valve to admit fresh air to each chamber, a poppet valve to admit waste gases from each chamber to the stack flue, whereby fresh air may be admitted in regulated quantities to each regenerator of either pair of regenerators while the stack flue may be connected to carry out waste gases from the remaining pair of regenerators.

3. A melting chamber, a gas burner therefor, and regenerator containing checker-work, a passage leading from the melting chamber to the upper part of one end of the regenerator, a passage for fresh air and waste gases, leading from the lower part of the other end of the regenerator, and a passage free from checker-work and extending across the rear end of the regenerator and communicating directly with the second passage, whereby friction of the air and waste gases passing between the regenerator and the second passage is lessened.

Signed at Pittsburgh, Pa., this 18th day of February, 1921.

HORACE E. SMYTHE.
